UNITED STATES PATENT OFFICE.

GEORGE H. THACHER, JR., OF ALBANY, NEW YORK, ASSIGNOR TO GEORGE H. THACHER, SR., OF ALBANY, NEW YORK.

DUMPING-GRAVE.

1,158,747.

Specification of Letters Patent.

Patented Nov. 2, 1915.

Application filed August 2, 1912. Serial No. 712,888.

To all whom it may concern:

Be it known that I, GEORGE H. THACHER, Jr., a citizen of the United States, residing at Albany, in the county of Albany, State 5 of New York, have invented certain new and useful Improvements in Dumping-Grates; and I do hereby declare the following to be a full, clear, and exact description of the invention, such as will enable others 10 skilled in the art to which it appertains to make and use the same.

The present invention relates to dumping grates for furnaces, and more particularly to one of comparatively inexpensive, durable and efficient construction which may be constructed in various sizes and shapes by employing the proper number of fuel-supporting members.

One object is to provide independently 20 removable and like fuel-supporting members normally locked together in a frame by disengageable locking means, whereby any one of the members may be readily replaced.

Another object is to arrange the fuel-supporting members in such manner that a continuous grate surface having through air-passages is provided.

Another object is to provide operating mechanism for independently tilting the 30 different grate sections to dump the fuel residue supported thereon without disturbing any of the other sections.

Another object is to provide operating mechanism and strengthening members well 35 below the grate surface in order to prevent unnecessary strain therein due to the heat of combustion, and in order to maintain efficient operation at all times.

Another object is to so connect the operating mechanism that the dumping sections 40 tend to keep their normal horizontal position and to return to that position from the position to which they may have been tilted by the operating mechanism.

Other desirable objects in construction 45 and operation will be apparent from the following description and the accompanying drawings, and will be specifically pointed out in the appended claims.

In the accompanying drawings illustrating 50 the preferred embodiment of my invention: Figure 1 is a plan view of my furnace grate; Fig. 2 is a section partly in elevation, on line 2-2 of Fig. 1; Fig. 3 is a section,

partly in elevation, on line 3-3 of Fig. 1; Fig. 4 is a section, partly in elevation, on line 4-4 of Fig. 1; Fig. 5 is a section, on line 5-5 of Fig. 6, particularly showing a supporting-frame for the fuel-supporting members; and Fig. 6 is a section, on line 6-6 of Fig. 5.

The furnace grate comprises an outer frame A inclosing the grate structure, which is made up of any number of dumping sections in longitudinal or transverse arrangement, wherein each dumping section may contain any number of supporting frames B in various arrangements with any number of fuel-supporting members C in each frame.

The grate shown comprises two dumping sections arranged end to end, five supporting frames B side by side in each section and three fuel supporting members C in each frame. The supporting frames B are compactly arranged and the fuel-supporting members C fastened therein abut those in the sidewise adjacent frames and overlap those in the endwise adjacent frames, so that a continuous grate surface is provided 80 throughout the furnace. The fuel-supporting members are perforated with through air-passages D which may aggregate any suitable percentage of the grate surface to meet the various requirements of fuel, draft, 85 etc. The supporting frames B are fastened together in groups to form independent dumping sections, and each dumping section is connected to operating mechanism E for independently tilting that section to dump 90 the fuel residue therefrom without disturbing the other dumping section.

The furnace frame A is made in any suitable way and has a journal surface for supporting the dumping section. The fuel-supporting frames B are identical, and are preferably cast in the form of a box-like structure open at the top and bottom and divided into compartments by the transverse strengthening partitions F. Each frame has a part G extending downwardly at a place to one side of the center of gravity of the frame for connection to the operating mechanism. The fuel-supporting members C are identical and are preferably cast with a flat fuel surface and a corrugated shaped bottom for cooling purposes, while long and narrow passages D extend through the mem-

bers for the entrance of the air to the coal or other combustible material on the fuel-supporting members.

The sides of the fuel-supporting members 5 are made perpendicular so as to abut against the sidewise adjacent members to form a continuous grate surface in a transverse direction, and the ends of the fuel-supporting members are made oblique so as to overlap 10 the complementary oblique ends of the adjacent members in the same frame and in the endwise adjacent frames so as to form a continuous grate surface in the longitudinal direction also. By this arrangement 15 either of the individual dumping sections may be tilted to the position shown in broken lines in Fig. 2 without disturbing the other dumping section. Each fuel supporting member has two legs H fitting 20 against the partition F of the frame. The rod I extending through holes in these legs forms locking means for normally fastening the fuel-supporting members in the frame B, but this rod may be disengaged 25 from the frame and the fuel-supporting members to replace any member at any time 30 that it may be burned out or otherwise made unfit for efficient service.

A transverse member J for each dumping section is fastened by pins K to all the downwardly extending parts G, from the supporting frames, and is provided with journals L adapted to turn in bearings in the frame A to allow tilting of the dumping section. 35 Each transverse member J has downwardly extending fingers M pivotally connected by a pin N to the operating bar E which extends outside the furnace so that it can be operated to tilt the respective grate sections 40 and thereby dump the fuel residue supported thereon. As previously noted the parts G are so arranged relatively to the supporting frames B that the unbalanced weight of the grate section always tends to hold the 45 fuel-supporting members in their normal horizontal condition to form a continuous grate surface and also tends to restore them to that position when they are tilted to dump the fuel residue. The abutments O 50 on the side frames P serve to keep the fuel supporting members in level position during 55 normal operation but do not interfere with the dumping movements previously described.

55 If desired, I may use cotter pins for fastening the fuel supporting members C in the frames B, as for example as shown on the right hand side of Fig. 3 at R.

Having thus described my invention, what

60 I claim is:

65 1. In a dumping grate for furnaces, the combination of a transverse rocking member having end trunnions adapted to turn in the furnace frames, means for rocking said member, a plurality of frames removably

supported and arranged side by side on said transverse rocking member and movable therewith when said mechanism is operated, any one of said frames being removable from said transverse rocking member independently of the others, and a plurality of fuel supporting elements fastened in each frame but removable therefrom, said elements completely covering their respective frames and thereby protecting them from 75 direct contact with the fire, substantially as described.

2. In a dumping grate for furnaces, the combination of a transverse rocking member adapted to turn in the furnace frames, 80 mechanism for swinging said transverse rocking member when the grate is to be dumped, a plurality of frames secured to and mounted on said transverse rocking member, said frames being positioned side 85 by side and each being removable independently of the others, and a plurality of perforated fuel supporting elements fastened in each frame but removable therefrom, said elements completely covering 90 their respective frames to protect them from direct contact with the fire, the abutting ends of said fuel supporting elements overlapping, substantially as described.

3. In a dumping grate for furnaces, the 95 combination of a plurality of transverse rocking members provided with end trunnions adapted to turn in the furnace frames, operating mechanism associated with each of said transverse members so that it may be 100 moved to dump the fuel residue, a plurality of frames arranged side by side on each of said transverse rocking members, each of said frames being removable from said rocking member independently of the others, 105 and a plurality of fuel supporting elements in each frame, said elements having overlapping edges in each frame to form a continuous fuel supporting surface completely 110 covering the frames and protecting them 115 from direct contact with the fire, the end elements of the frames on one transverse rocking member overlapping the end elements of the frames of the adjacent rocking member to form a fuel supporting surface, part of which can be dumped while the remainder is stationary, and any frame of which can be removed for renewal or adjustment of its attached fuel supporting elements without removal of adjacent frames. 120

4. In a dumping grate for furnaces, a plurality of dumping sections arranged end to end, wherein each section comprises a plurality of elements abutting at their sides and wherein each element comprises a supporting frame and a plurality of independently removable perforated fuel supporting members with overlapped ends fastened in the frame to form a continuous 125 grate surface in transverse and longitudinal 130

nal directions, said fuel supporting members completely covering said frame and protecting it from direct contact with the fire, a transverse member arranged to fasten the 5 elements of each dumping section together and provided with end bearings adapted to turn in the furnace frame, and operating mechanism associated with each transverse member for tilting the fuel supporting 10 members of the respective sections to dump the fuel residue therefrom without disturbing other sections.

5. In a dumping grate for furnaces, a plurality of dumping sections arranged end to 15 end, wherein each section comprises a plurality of elements abutting at their sides and wherein each element comprises a supporting frame and a plurality of independently removable perforated fuel 20 supporting members fastened in the frame to

form a continuous grate surface in transverse and longitudinal directions, said fuel supporting members completely covering said frame and protecting it from direct contact with the fire, a transverse rocking member 25 arranged to fasten the elements of each dumping section together and provided with end bearings adapted to turn in the furnace frames, and operating mechanism associated with each transverse member for tilt- 30 ing the fuel supporting members of the respective sections to dump the fuel residue therefrom.

In testimony whereof I affix my signature, in presence of two witnesses.

GEO. H. THACHER, JR.
